UNITED STATES PATENT OFFICE.

WILLIAM F. HOHORST, OF SAN DIEGO, CALIFORNIA.

DRY-DOCK.

1,296,662.

Specification of Letters Patent. Patented Mar. 11, 1919.

Application filed August 6, 1918. Serial No. 243,589.

To all whom it may concern:

Be it known that I, WILLIAM F. HOHORST, a citizen of the United States, and a resident of San Diego, in the county of San Diego, 5 and State of California, have invented a new and Improved Dry-Dock, of which the following is a description.

My invention relates to dry docks and more particularly to floating dry docks in 10 which a float or caisson is formed with an open under side, whereby the water may be displaced therefrom by air under pressure to float the dock.

The general object of my invention is to 15 provide a floating dock of the indicated character having characteristics and advantages as will appear.

Reference is to be had to the accompanying drawings forming a part of this specification, 20 it being understood that the drawings are merely illustrative of one example of the invention.

Figure 1 is a front view of a floating dry dock embodying my invention;

Fig. 2 is a partly sectional front view of a 25 portion of one of the floatable sections;

Fig. 2^a is a fragmentary vertical section showing a portion of one of the partitions in the float sections, and a check valve 30 therein;

Fig. 3 is a partial plan view of a dry dock embodying my invention;

Fig. 4 is an end view of one of the sections and relatively fixed guide racks therefor.

In carrying out my invention in accordance with the illustrated example, piers 35 10 are provided. Separate floatable sections 11 are disposed extending substantially from one pier to the other. In order that the sections 11 in rising and falling may be constrained to have a parallel movement and be prevented from tilting in any direction, fixed vertical racks 12 are provided at opposed sides of the piers 10 and a train of intermeshing gears 13 is provided on shafts 14, 40 extending lengthwise of each section 11.

The various sections 11 comprising the float in practice are adapted to receive a vessel A to be supported on keel blocks B and 45 bilge blocks C in the usual manner, said blocks and vessel being conventionally indicated.

Each section 11 is open at the under side and is compartmented, being divided by vertical

partitions 15. Air under pressure is supplied to the central compartments through an inlet 16 leading to one of said compartments and the partition 15 between the two central compartments has an opening 17 therein near the top thereof for establishing communication between said central compartments so that water will be displaced equally from the two compartments under the pressure of the air supplied through the inlet 16. Also, in those partitions 15 dividing the other compartments from one another and from the adjacent central compartments, ports 17^a are provided near the lower edges of said partitions, so that upon a given displacement of water from the central compartments should the buoyancy thus obtained be insufficient to lift the load, successive lateral compartments will automatically cut in by air from the central compartments entering adjacent compartments through the ports 17^a. In addition to the automatic communication provided for through the ports 17^a, by-passes are provided between adjacent compartments through the medium of pipes 18 connecting with each of 20 two compartments and manually controlled by a cut-off valve 19. Vent valves 20 are provided in the top of each compartment, except the central ones, and similarly in the partitions 15 vent valves or air valves 21 are provided near the top except in the central partition. The valves 20 and 21 may be alike and as shown in Fig. 2^a including a spring-pressed ball valve 22. Thus, with the rising of the float section for example under 25 the displacement of the water in the central compartments of the section, a vacuum will be prevented in the other compartments, by air entering through vent valves 20. Upon the lowering of the sections air will 30 pass through the valves 21 to the central compartments and outward through the inlet 16 and to the atmosphere at any point in the pipe lines hereinafter referred to. The piers 10 are provided with preferably 35 conical air-storage chambers 23 and passages 24 extending from the chambers through the top of the piers whereby the said chambers may be connected with the float sections 16 to receive air therefrom and as later explained in the lowering of the dock sections.

To supply air under pressure any suitable source of compressed air may be provided,

there being indicated conventionally an air compressor 25 from which a manifold or pipe line 26 extends along a pier 10 and branches 27 extend from said manifold to make connection with the respective sections. Permanent pipe lines 29 may be provided on each section 11 adapted to be connected with the branch 27 by a hose 28. Each branch has a two-way valve 30 which 10 may connect a branch 27 with the hose 28 or permit outflow to the atmosphere through a discharge 31 in permitting the air to escape from the section 11. Also, suitable means is provided to connect up an air passage 24 of a chamber 23 with the sections 11, one means for the purpose being indicated in Fig. 1 where a branch pipe 32 connects a branch 27 to a valve 33 leading to a passage 24, said valve being adapted to connect a 15 passage 34 with the branch 32 or discharge to the atmosphere.

The described construction provides for establishing communication between the several compartments of a section to supply 25 air under pressure thereto as desired or required under given load conditions and the supply and equalization of the air is effected while employing a single air inlet which makes for simplicity of construction and 30 facility in the operation and control of the dock.

An advantage of a dock as described above 35 also is that the floatable sections may be completely submerged and the dock then be utilized for commercial docking purposes, it being necessary only that there be sufficient water in the dock for the submergence of the floatable sections below the depth required to adapt the dock for general docking 40 purposes.

I would state in conclusion that while the 45 illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I

Copies of this patent may be obtained for five cents each, by addressing the "Commissioner of Patents, Washington, D. C."

claim as new, and desire to secure by Letters Patent:

1. A dry dock including a floatable structure, partitions therein dividing the same into compartments, said structure being open at the under side, means to direct air pressure to the central compartments to displace the water therefrom, means to permit entrance of air to the compartments other than the central compartments upon the rising of the structure, and means adapted to permit air to escape from the compartments other than the central ones to the latter upon lowering of the structure.

2. A dry dock including a floatable structure open at the under side, partitions dividing said structure into compartments, and means to direct air under pressure to the central compartments to displace the water therefrom, the partitions except that of the central ones having openings near the bottom to admit air from the central compartments upon a predetermined displacement of the water from said central compartments.

3. A dry dock including a hollow pier forming an air chamber, a floatable structure open at the under side, means to supply air under pressure to said structure, connections between said supply means and said structure to admit air to the latter for displacing the water therefrom, and manually controlled means to establish connections between the supply means and said structure or between the hollow pier and said structure to direct air from said supply means to the structure or from said structure to the hollow pier and return the air from the pier to said structure.

4. A dry dock including a floatable structure open at the under side, vertical partitions dividing the structure into compartments, and means for directing air under pressure to the central compartments to displace the water therefrom, said compartments communicating with the lateral compartments by means arranged below the tops of the said compartments for the purpose specified.

WILLIAM F. HOHORST.
